UNITED STATES PATENT OFFICE

ELMER ELLSWORTH CHILDS, OF JACKSON HEIGHTS, NEW YORK, ASSIGNOR TO CHILDS COMPANY, OF NEW YORK, N. Y., A CORPORATION OF NEW YORK

DESIGN FOR A RESTAURANT ORDER CHECK

Application filed March 7, 1927. Serial No. 21,001. Term of patent 14 years.

To all whom it may concern:

Be it known that I, ELMER ELLSWORTH CHILDS, a citizen of the United States, and a resident of Jackson Heights, in the county of Queens and State of New York, have invented a new, original, and ornamental Design for Restaurant Order Check, of which the following is a specification, reference being had to the accompanying drawing, forming part thereof.

The figure is a plan view of a restaurant order check, showing my new design.

I claim:

The ornamental design for a restaurant order check, as shown.

E. ELLSWORTH CHILDS.
